UNITED STATES PATENT OFFICE

EDWARD N. WINSLOW, OF SHAKER HEIGHTS, OHIO, ASSIGNOR TO THE MILLS COMPANY, OF CLEVELAND, OHIO, A CORPORATION OF OHIO

SHEET-METAL PANEL

Application filed September 11, 1930. Serial No. 481,157.

This invention relates to sheet metal constructions, and more particularly to sheet metal panels which are suitable for, or employed in the production of, doors and partitions.

It is the general object of the invention to provide a construction of this character which will enable such panels or partitions to be constructed from a minimum number of 10 like or identical units; also to construct the units in such manner as to enable two such units to be quickly and conveniently assembled. A still further object of the invention is to provide means whereby said panels 15 may be constructed at a comparatively low expense and with rapidity of production and ease of assemblage.

I secure the foregoing objects and other objects which appear hereinafter, through 20 the construction and arrangement of parts shown in the drawings, wherein Fig. 1 represents a perspective view of a panel constructed in accordance with my invention; Figs. 2 and 3 are details in section corresponding 25 respectively to the lines 2—2 and 3—3 of Fig. 1; Fig. 4 a view, similar to Fig. 2, showing the units in the positions which they occupy during the assembling operation and prior to the interlocking of the flanges; Fig. 30 5 is a plan view of one of the units, the other unit being shown in dot-and-dash line and the units occupying the positions shown in Fig. 4; Fig. 6 a side elevation of one of the units; Fig. 7 a sectional view through one 35 of the units, corresponding substantially to the line 7—7 of Fig. 5; and Fig. 8 a sectional detail showing a modification of the joint shown in the preceding views.

Describing the various parts by reference 40 characters, A and B represent generally two similar sheet metal units which, when assembled, constitute the metal parts of a panel. Where the panel is square, the units A and B may be identical in the construction and arrangement of the parts thereof, thus requiring 45 in fact the manufacture of a plurality of single units for the production of such panels. However, when the panel is rectangular in shape, as shown herein, two similar 50 units (a right and a left) will be required.

The unit A comprises a flat rectangular metal sheet 1 having one of its longitudinal edges and one of its lateral edges provided with a wide side flange, indicated at 2 and 3, respectively, and constituting two of the 55 sides of the panel or partition. Each of the side flanges 2 and 3 is provided with an end flange 2^a and 3^a respectively, which end flanges are parallel, or nearly parallel, with the body of the sheet 1, to insure a closed joint, 60 said flanges extending beneath such body.

The opposite unit B is also provided with a flat rectangular metal sheet 4 of the same dimensions as the corresponding sheet of the unit A and having at one of its longitudinal edges a side flange 5 and at one of its lateral edges a side flange 6, each of the flanges 5 and 6 having a flange 5^a and 6^a, respectively, 65 which are parallel with the body of the sheet 4 and extend thereabove.

In addition, the panel A has the metal at the edge opposite the edge 3 provided with a U-shaped seat formed by bending the entire length or width of the metal at such edge 70 backwardly upon itself beneath the under surface of the sheet 1, as shown at 7, and then bending such metal upon itself to provide a flange 8 extending outwardly parallel with the part 7, and forming a grooved seat 9 therebetween—see Fig. 4. It also has the 75 lateral edge opposite the side 2 provided with a similar seat, the parts 10, 11 and 12 corresponding respectively to the parts 7, 8 and 9 of the seat just described—see Fig. 3. The distance of the first bending edge from the 80 body of each sheet may be varied by folding the edge over any thickness of spacer, to bring the exterior joint at the desired location on the edge; see Figs. 4 and 8.

The edge of the sheet 4 which is opposite 85 the edge 6 is provided with a U-shaped seat similar to those just described for the sheet 1, the parts of the seat being indicated at 13, 14 and 15; and the edge of the sheet 4 which is opposite the edge 5 is also provided with a 90 U-shaped seat similar to those hereinbefore described and the parts of which are indicated at 16, 17 and 18—see Fig. 3.

In order to permit the folding of the metal 95 to form the U-shaped seats, the corners of 100

each sheet are first cut away so as to enable the metal, when folded into such U-shape, to present beveled edges at the ends of both seat flanges, such as shown at 13^a and 16^a.

- 5 With the parts constructed and arranged as described, the inner surfaces of the sheets or panels 1 and 4 will be coated each with a suitable adhesive, as glue, indicated at C. A pad D of insulating material, such as corrugated cardboard, or porous fiber, is secured to the inner face of one of these sheets, after which the other unit is applied on top of the pad, in the manner indicated in dot-and-dash lines in Fig. 5, with the side flanges of 10 one unit registering with the U-shaped seats of the other unit. Then, by a short movement in a diagonal direction, as indicated in Fig. 5, the units A and B will be assembled, together with the interposed insulating pad D. 15 20 The pad D may, as shown, cover the entire space between the units; or, if desired, it may be partly or entirely eliminated.

The corners between the side flanges 2 and 3 and between the side flanges 5 and 6 may 25 be closed by solder or any of the well-known metal fillers and, after the units with the interposed pad shall have been assembled, the other corners will preferably be closed in the same manner.

- 30 In Fig. 8, there is shown a modification of the invention wherein the flanges and U-shaped seats are formed at a distance from the bodies of the sheet metal units. In this view, one of the flanges of the sheet metal 35 unit A' is indicated at X and one of the U-shaped seats of the unit B' is indicated at Y. It will be noted that the joint formed between the two units is here shown as approximately half the depth of the edge of the 40 assembly. As is the case with the form of my invention shown in the preceding views, two of the adjacent side edges of the unit A' will be provided with the flanges X while the other two will be provided with U-shaped 45 seats similar to the seat Y. In like manner, two of the adjacent edges of the unit B' will be provided with the U-shaped seats shown in Fig. 8, while the other two edges will be provided with flanges similar to the flange X.

- 50 Due to the manner of constructing the parts entering into the construction of each panel, it is possible to construct such panels from sheet metal and with a minimum of expense, due to the fact that, at most, only one 55 pair of like sheet-metal units will be required for each panel; and, in the event that the panels are to be square in outline, then only one set of units need be constructed. Furthermore, by this construction, I am enabled 60 to produce a flush panel, which may be used as a door or partition, and to secure this result by interlocking two like metal units.

Having thus described my invention, what I claim is:

- 65 1. A panel comprising a pair of sheet metal

units each comprising a rectangular sheet metal body having integral sides projecting from two adjacent edges, each side having at the end remote from the body of the sheet a flange extending from such edge substantially parallel with the body of the sheet and toward the edge of such sheet which is opposite the said flange, and each unit also having each of its other two edges provided each with a U-shaped seat adjacent to the inner 75 surface of each such sheet and formed by bending the metal at each such edge backwardly beneath the body of such sheet and then outwardly, the flanges provided on the sides of each unit being adapted to enter the 80 U-shaped seats of the other unit whereby the units may be assembled by a diagonal movement of one unit with respect to the other after registering the flanges with their respective seats.

2. A sheet metal panel comprising a pair of symmetrical sheet metal rectangular units each having two adjacent edges provided each with an integral inwardly extending seat-engaging member and each of the other two edges of each unit being provided with an inwardly extending seat, and means whereby the seat-engaging members of one unit may be interlocked with the seats of the other unit by movement of the said units 95 toward each other in a diagonal direction during the assembling operation.

3. A sheet metal panel comprising a pair of symmetrical sheet metal rectangular units each having two adjacent edges provided each with a side, each side terminating in a flange directed at right angles thereto beneath the body of such unit and each of the other edges of each unit being provided with a U-shaped seat adjacent the under or inner 100 surface of such unit, the flanges of each unit being adapted to enter the seats provided in the other unit, whereby the units may be assembled and interlocked by registering the flanges of each unit with the seats of the other 110 unit and moving one of said units diagonally with respect to the other.

4. A sheet metal panel comprising a pair of units each having a rectangular body provided at two adjacent edges with sides and each side having a flange at the edge thereof remote from such body extending substantially parallel with and beneath the body and each of the other edges of each such body having a U-shaped seat therebeneath, whereby the units may be assembled in interlocked relation by entering the flanges of each of the units into the seats of the other unit, and an insulating filling interposed between the said units so assembled.

5. A sheet metal panel comprising a pair of units each having a rectangular body provided with sides, each of two adjacent sides of each unit having a flange at the edge thereof which is remote from such body and 130

extending substantially parallel with and beneath the body and each of the other sides of each such unit having a U-shaped seat extending therebeneath, whereby the units 5 may be assembled in interlocked relation by entering the flanges of each of the units into the seats of the other unit and by relative movement of the units after so entering the flanges into the said seats.

10 6. A sheet metal panel comprising a pair of symmetrical sheet metal rectangular units each having sides, two adjacent sides of each unit being provided each with an integral projection and each of the other two sides of 15 each unit being provided with an inwardly extending seat, and means whereby the projections of one unit may be interlocked with the seats of the other unit by a movement of the said units toward each other in a diagonal 20 direction during the assembling operation.

7. A sheet metal panel comprising a pair of units each having a rectangular body provided with sides, each of two adjacent sides of each unit having an inwardly extending 25 flange at the edge thereof spaced from said body and extending substantially parallel therewith and each of the other sides of each such unit having an inwardly extending U-shaped seat spaced from such body and extending substantially parallel thereto, whereby the units may be assembled in interlocked 30 relation by entering the flanges of each of the units into the seats of the other unit and by relative movement of the units after so 35 entering the flanges into the said seats.

8. A sheet metal panel comprising a pair of units each having a rectangular body provided with sides, each of two adjacent sides of each unit having an inwardly extending 40 flange at the edge thereof spaced from such body and each of the other sides of each such unit having an inwardly extending U-shaped seat spaced from such body whereby the units may be assembled in interlocked relation by 45 entering the flanges of each of the units into the seats of the other unit and by relative movement of the units after so entering the flanges into the said seats.

In testimony whereof, I hereunto affix my
50 signature.

EDWARD N. WINSLOW.
